DEVICE FOR PUNCHING AND PLUGGING CANS

Filed Dec. 28, 1926

Inventor

E. O. Burns

By *Watson E. Coleman*

Attorney

UNITED STATES PATENT OFFICE.

EUGENE O. BURNS, OF RENO, NEVADA.

DEVICE FOR PUNCHING AND PLUGGING CANS.

Application filed December 28, 1926. Serial No. 157,577.

This invention relates to devices for punching holes in sheet metal cans such as condensed milk cans or varnish cans, salad oil cans, or the like.

5 One of the objects of the present invention is to provide a device of this character which is so formed that it may be used to punch two sizes of holes in the can.

Another object of the invention is to provide a detachable handle for the punching device which, when removed from the punching device, may be used for enlarging the hole initially punched by the device.

10 A further object is to provide a punching device which will be also used as a plug to close the opening in the can.

15 My invention is illustrated in the accompanying drawings wherein:—

Figure 1 is an elevation of my improved 20 implement showing it as used for perforating a tin shown in section;

Fig. 2 is a fragmentary elevation partly in section of my implement greatly enlarged, showing the handle detached from the body.

25 Referring to these drawings it will be seen that the device comprises a body which has an enlarged or bulbous portion 11, a constricted neck 12, and a disk-like portion 13. The head 11 is formed with a longitudinally extending bore 14. Integral with the body is a shank 15, the upper end of which is defined by a shoulder 16 inclined upward and outward. The extremity of the shank is pointed as at 17, and between this pointed 30 extremity and the middle portion of the shank, the shank is reduced in diameter as at 18, and a beveled or inclined shoulder 19 is formed between these two portions of the shank.

35 Coacting with the head, is the handle 20 which is preferably formed of a single piece of metal bent upon itself to provide convergent legs 21. These legs at their outer ends are extended parallel to each other, as 40 at 22, the inner faces of the legs being flat so that the legs will fit against each other and may be fitted within the bore 14.

45 In the use of this device, the handle is disposed within the bore 14 and by this means 50 the punch is forced into the can. If only a relatively small opening is desired, only the lower portion of the punch is forced through the can but if a larger opening is desired, the punch is further forced inward past the

shoulder 19. The shank 15 with the body 55 may be left within the hole punched so as to act as a plug and be withdrawn whenever required. If it be desired to make a larger hole than is possible to be made by the shank 15, then the end 22 of the handle is 60 inserted in the punched opening and the handle may be forced inward, which will make an elongated opening in the can of any length within the range of the handle. Attention is called to the fact that the handle 65 may also be used as a pair of tweezers if desired, which is convenient for pulling slivers and other like operations and the punch formed of the pointed shank and the handle may be used for embroidery work 70 as a bodkin. The device will preferably be made of iron, steel, or any hard metal.

This punch is designed to be made in two different sizes from one-eighth to five-sixteenths of an inch. Obviously, however, the 75 particular size is immaterial as many changes might be made in the details of construction and arrangement of parts without departing from the spirit of the invention as defined in the appended claims.

80 I claim:—

1. A combination punch and plug of the character described including a body having a head formed with a bore, a shank extending from the body and pointed at its outer end, a portion of the shank extending from said point being less in diameter than that portion of the shank adjacent the body, and a handle having one end insertible within said bore and having a diameter approximately the same as that portion of the shank adjacent the body, said handle having opposed faces diverging outward from that extremity of the handle which is insertible into said bore whereby the handle 90 may be used for expanding a hole punched by the bore.

2. A combination punch and plug of the character described including a body having a head formed with a bore, a shank extending from the body and pointed at its outer end, a portion of the shank extending from said point being less in diameter than that portion of the shank adjacent the body, and a handle having one end insertible within said bore, the handle being formed of a single piece of metal bent upon itself to provide two converging legs, the extremi- 100 105

ties of the legs being parallel to each other and fitting against each other and insertible in the bore.

3. An implement of the character described including a body formed with a bulbous head and a disk-like portion, a shank extending from the body and having two diameters connected by an intermediate beveled portion, the extremity of the shank 10 being pointed, said head having a longitudinally extending bore, and a handle having a contracted extremity insertible into and fitting said bore and having a diameter approximately the same as that portion of the 15 shank adjacent the body, the handle being formed to provide two upwardly diverging side faces extending from said insertible portion of the handle and constituting

means whereby the handle may be used to enlarge an opening formed by the bore.

4. A combination punch and plug of the character described comprising a body 20 formed with a shank, the shank being pointed and the body having a longitudinally extending bore having a diameter approximately equal to that of the shank, and a 25 handle having one end adapted to fit within the bore but removable therefrom, the handle having upwardly divergent opposed faces extending upward from the insertible end of the handle whereby the handle may 30 be used to increase the size of an opening formed by the shank.

In testimony whereof I hereunto affix my signature.

EUGENE O. BURNS.
